UNITED STATES PATENT OFFICE

168,798

TELEVISION CABINET

Leslie G. Martin, Rochester, N. Y., assignor to
Stromberg-Carlson Company, a corporation of
New York

Application May 7, 1952, Serial No. 19,625

Term of patent 14 years

(Cl. D56—4)

To all whom it may concern:

Be it known that I, Leslie G. Martin, a citizen of the United States, residing at Rochester, State of New York, have invented a new, original, and ornamental Design for a Television Cabinet, of which the following is a specification, reference being had to the accompanying drawings, forming a part hereof in which

Fig. 1 is a perspective view of a television cabinet showing my new design with the doors in closed position; and

Fig. 2 is a similar view thereof with the doors in open position.

The unshown side is similar to the shown side. The back is plain.

I claim:

The ornamental design for a television cabinet, as shown and described.

LESLIE G. MARTIN.
